(57) **CLAIM**

The ornamental design for a culinary knife, as shown and described.

DESCRIPTION

FIG. 1 is a side view of one side of the culinary knife according to one embodiment of my new design;

FIG. 2 is a perspective view of one side, back, and bottom of the culinary knife according to a second embodiment of my new design;

FIG. 3 is a top view thereof; and,

FIG. 4 is a perspective of the opposite side, back, and bottom thereof.

The broken lines shown represent portions of the culinary knife that form no part of the claimed design.
